ATT'YS.,

UNITED STATES PATENT OFFICE.

OTTO L. RAABE, OF JERSEY CITY, NEW JERSEY, ASSIGNOR TO R. HOE AND CO., OF NEW YORK, N. Y., A CORPORATION OF NEW YORK.

PRINTING CYLINDER.

Application filed November 15, 1921. Serial No. 515,226.

To all whom it may concern:

Be it known that I, OTTO L. RAABE, a citizen of the United States, residing at Jersey City, county of Hudson, and State of New Jersey, have invented certain new and useful Improvements in Printing Cylinders, fully described and represented in the following specification and the accompanying drawings, forming a part of the same.

10 This invention relates to certain improvements in printing cylinders, and particularly to an improved arrangement of the plates on the cylinder.

It is the especial object of the invention to 15 provide a construction embodying a cylinder having more than two plates arranged in line across the cylinder in which the plates are positioned on the cylinder in staggered relation with each other, the stagger being 20 such that the leading ends of no two plates are in line, so that there will be only one space left to form the margin between two plates where the cylinder is capacitated to carry two plates around, or between the head 25 and tail end of the plate where the cylinder is capacitated to carry one plate around, at any given line across the cylinder, this construction affording an increase in the supporting surface for the impression cylinder 30 and the inking rolls, and so on which bear against the forms, over the staggered plate constructions heretofore used.

It is a further object of the invention to 35 produce a corresponding impression cylinder having the blanket openings corresponding in position to the position of the margin spaces, these openings being staggered similarly to the staggering of the plates.

With these and other objects not specifically referred to, the invention consists in 40 certain novel parts, combinations and arrangements, which will be described in connection with the accompanying drawings and the novel features then pointed out in 45 the claims hereunto annexed.

In these drawings—

Figure 1 is a side elevation of a printing couple embodying the invention; and

Figure 2 is an end view partly in section 50 of the construction shown in Fig. 1.

Referring now to these drawings, there is illustrated a plate cylinder having three plates arranged in line across the cylinder, the columns of the plates in the particular

construction illustrated running lengthwise 55 thereof and the cylinders being capacitated to carry two plates around. While the invention is particularly applicable to a cylinder having three plates across, it will be understood that the invention is not limited to 60 this number but may be employed with cylinders capacitated to carry more than three plates across.

In the drawings the form cylinder is indicated by the letter A, this form cylinder being of any usual construction, as a hollow roll or drum provided with interior strengthening ribs or braces, and this cylinder is mounted on a suitable shaft a. In the particular construction illustrated this cylinder 65 is capacitated to carry two plates around and three plates wide, there thus being six plates on the cylinder, these plates being marked 1, 2, 3, 4, 5 and 6. In accordance 70 with the invention these plates are arranged on the cylinder in staggered relation to each other. The amount of this stagger may vary, but it will however be more than the width of a margin space so that no two margin spaces are in line with each other across the cylinder, and in the particular construction 75 shown this stagger is about 120°.

Between each two succeeding plates around the cylinder are the usual margin bars 7, these margin bars being secured to 80 the cylinder surface in any usual or suitable manner, these margin bars acting as plate stops and providing the margin spaces. The plates are locked up on the cylinder in any 85 usual or suitable manner. As for instance 90 there is provided a margin ring 8 extending around the cylinder and the plates 5, 6 are locked against this ring by clamps 9 operated by clamp operating rods 10. Similarly 95 plates 3 and 4 are locked at one side against the ring 8 and on the other side by sliding clamps 11, which are moved to locking position by the plates 1 and 2, these plates 1 and 2 in turn being locked in position by 100 clamps 12 operated by clamp operating rods 13 from outside the end of the cylinder.

With this construction where the cylinder is capacitated to carry three plates wide only one margin space appears on any one line across the cylinder, the impression cylinder and rolls thus being supported across the cylinder for approximately two thirds of the cylinder width. This increase in the 105

support for the impression member and the rolls materially reduce pounding as the cylinders pass over the margin gaps, and a rigid smooth running construction is produced.

5 Co-operating with the form cylinder are impression means which, in the particular construction illustrated, is a cylinder B formed with a blanket supporting surface 16 and strengthening webs 17. This cylinder is provided with blankets, three blankets being shown, one for each set of plates on the form cylinder, these blankets being marked 18, 19 and 20. Slots 21 are formed in the cylinder wall through which the ends 10 of the blankets pass and these blankets are adjusted on the cylinder by the usual blanket adjusting mechanisms, one of these mechanisms being provided for each blanket and operable in any desired manner, as for instance two of the blankets may be adjusted 15 from one end of the cylinder, and one of the blankets from the other end. These blanket adjusting mechanisms comprise the usual rod 22 carrying a ratchet 23 controlled by pawls 24, by turning which rods the blankets may be adjusted as desired. The blanket openings are, as illustrated, staggered to 20 correspond with the staggering of the plates.

With this construction a strong, rigid and 25 smooth running arrangement is provided. While the invention is especially applicable to three plates across the cylinder, more than three plates may be employed as desired and the degree of the stagger may be varied as 30 required, and the invention is not to be restricted to the use of three plates or to the particular amount of stagger shown.

What I claim is:

1. In combination, a form cylinder having 35 more than two plates arranged in line across the cylinder, said plates being so staggered with respect to each other that the leading edges of no two plates are in line across the

cylinder, and co-operating impression means.

2. In combination, a form cylinder having 45 more than two plates arranged in line across the cylinder with a margin space at the head and tail of each plate, said plates being staggered with respect to each other with a stagger greater than the width of a margin space so that the leading edges of no two plates are in line across the cylinder, and co-operating impression means.

3. In combination, a form cylinder having 55 more than two plates arranged in line across the cylinder with a margin space at the head and tail of each plate, and said plates being staggered with relation to each other with a stagger greater than the width of a margin space, and a co-operating impression cylinder having blankets, and blanket openings staggered correspondingly with the stagger of the plates.

4. In combination, a form cylinder having 60 three plates arranged in line across the cylinder with a margin space at the head and tail of each plate said plates being staggered with respect to each other with a stagger greater than the width of a margin space so that the leading edges of no two plates are 65 in line across the cylinder, and co-operating impression means.

5. In combination, a form cylinder having 70 three plates arranged in line across the cylinder with a margin space at the head and tail of each plate said plates being staggered with respect to each other with a stagger greater than the width of a margin space so that the leading edges of no two plates are 75 in line across the cylinder, and a co-operating impression cylinder having three blankets and blanket openings staggered correspondingly with the stagger of the plates.

In testimony whereof, I have hereunto set my hand.

OTTO L. RAABE.
